UNITED STATES PATENT OFFICE.

JOEL W. MILLICAN, OF FORT WORTH, TEXAS, ASSIGNOR OF ONE-HALF TO JAMES E. NORRIS, OF FORT WORTH, TEXAS.

AEROPLANE.

1,203,383.

Specification of Letters Patent. Patented Oct. 31, 1916.

Application filed February 2, 1916. Serial No. 75,724.

To all whom it may concern:
Be it known that I, JOEL W. MILLICAN, a citizen of the United States, residing at Fort Worth, in the county of Tarrant and State of Texas, have invented certain new and useful Improvements in Aeroplanes; and I do hereby declare the following to be a full, clear, and exact description of the invention, such as will enable others skilled in the art to which it appertains to make and use the same.

The invention relates to improvements in aeroplanes.

The object of the present invention is to improve the construction of aeroplanes and to provide a simple, practical and efficient aeroplane of comparatively inexpensive construction equipped with a gas bag or drum of fire-proof construction adapted to enable an aeroplane to float safely and with ease and capable of eliminating dips to the ground and of increasing the carrying capacity of the aeroplane and of enabling the machine to ride without a long run, and readily alighting in a comparatively small space.

It is also an object of the invention to provide an aeroplane of this character equipped with a plane having a plurality of air pockets adapted to keep the plane balanced in the air and of thereby increasing the stability, safety and ease of handling the flying machine.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings Figure 1 is a plan view of an aeroplane constructed in accordance with this invention, Fig. 2 is a detail plan view of the rear portion of the aeroplane illustrating the construction of the tail plane, Fig. 3 is a side elevation of the aeroplane, Fig. 4 is a detail side elevation of the rear portion of the aeroplane, illustrating the manner of mounting the tail plane for piv-

otal movement, Fig. 5 is a front elevation of the aeroplane, Fig. 6 is a side view of the 55 gas bag or drum partly in section, Fig. 7 is a transverse sectional view of the same, Fig. 8 is a detail view of a portion of the drum or gas bag, Fig. 9 is a detail sectional view of one of the valves. 60

Like numerals of reference designate corresponding parts in the several figures of the drawings.

In the accompanying drawings in which is illustrated the preferred embodiment of 65 the invention, the aeroplane comprises in its construction, a suitable supporting frame 1 provided with front and rear wheels 2 and 3 and designed to be constructed of light, tough material of any desired character 70 and to be suitably braced and stayed to form a frame of the desired strength. The frame supports a longitudinal gas bag 4 in the form of a cylinder or drum and designed to be constructed of heavy fabric such as 75 duck and to be covered with asbestos 5 or other fireproofing material to render it fire-proof and the said cylindrical gas bag which is inflated by the means hereinafter described is divided into a series of separate 80 chambers or compartments 6 by transverse partitions 7 so that in event of the puncture of one or more of the compartments, the gas bag will not entirely collapse and the remaining compartments will enable the flying machine to alight with safety. 85

The gas bag which is designed to extend substantially the entire length of the frame of the machine increases the carrying capacity of the same and renders the machine 90 safe and easily operated. The aeroplane by reason of the gas bag will float easily and safely and it will be adapted when the gas bag is properly inflated to rise without a long run and by deflating one or more of 95 the sections or compartments of the gas bag a descent and landing may be made as gently as desired without the usual dips ordinarily required by aeroplanes to accomplish a landing.

100 The gas bag is supplied with gas by a longitudinally disposed pipe 8 preferably located beneath the bottom of the gas bag and connected with the compartments 6 centrally of the bottoms thereof by branches 9 105 having suitable automatic valves 10. The

pipe 8 is provided with a central branch 11 which is designed to be connected with a pump and when the gas is forced through the pipe 8, the valves of the branch pipes 9 will open and an even pressure will be supplied to each of the chambers or compartments. Each of the valves preferably consists of a valve casing provided at the bottom with a seat and having a ball 12 normally arranged upon the seat and adapted to be moved upward therefrom by the pressure of the in-flowing gas. Any other suitable valves may be employed and suitable means will be provided for deflating one or 15 more of the compartments when it is desired to cause the aeroplane to descend.

The aeroplane is provided at the front portion above the front end of the gas bag with a top plane 13 of substantially oblong 20 form disposed transversely of the frame and supported by suitable uprights 14 and arranged in a horizontal position when the flying machine is horizontal. The top plane 13 is provided at opposite sides with gas 25 pockets 15 preferably of cylindrical form and constructed of heavy fabric or other suitable material and connected by branch tubes 16 with a pipe 17 leading to the bottom gas pipe 8. The top plane which is 30 maintained properly balanced in the air by the air pockets is designed to be covered with fire-proofing material and while a pair of gas pockets is shown, any number may of course be employed. The longitudinal gas 35 bag is supported at its ends by hangers 18 and is maintained in proper position by braces 19 extending over the top of the gas bag and suitably secured to the framework of the machine.

40 The flying machine is provided with laterally extending side planes 20 of substantially rectangular form suitably secured to the frame of the machine and extending outwardly therefrom at the bottom of the cylindrical gas bag as clearly illustrated in Fig. 5 of the drawings.

The side planes may be of any desired 45 size and they are designed in practice to be suitably braced and secured by stay wires or other suitable means to provide a light, rigid structure of the desired strength. At the back of the aeroplane, preferably at opposite sides of the gas bag are back planes 50 21 preferably located near the horizontal plane of the center of the gas bag and slightly above the same as shown but they may be arranged at any other desired point and they have approximately oblong front 55 portions 21 disposed in overlapping relation with the rear portions of the side planes 20 as clearly illustrated in Fig. 1 of the drawings. The body portions of the back planes taper forwardly as shown and are approximately dove-tail shape. These back 60 planes may be mounted and braced in any

desired manner to secure the requisite rigidity and strength.

The flying machine is equipped at its rear end with a tail vane 22 provided with a substantially U-shaped frame 23 having inwardly extending pivots 24 located intermediate of the ends of the frame and mounted in suitable bearings of the main frame whereby the tail vane is pivotally connected therewith and is adapted to swing upwardly and downwardly from a horizontal position to direct the aeroplane either upwardly or downwardly in its flight. The frame of the tail frame is equipped with front arms 25 located in advance of the pivots 24 and preferably operating in suitable arcuate guides 26. The frame is also equipped with upwardly and downwardly projecting arms 27 to which are connected wires 28 and 29 which are guided by pulleys 30 to suitable operating levers 31 and 32 located in front of a pilot seat 33 and adapted to be oscillated to swing the tail vane upwardly and downwardly. Any other suitable operating means may of course be employed.

The aeroplane is provided at the top in rear of the top plane 13 with a longitudinally disposed steering or guiding plane 34 tapered forwardly and provided at its front and rear ends with pivots 35 and 36, the front pivot 35 being journaled at the front of the top plane 13 and the rear pivot 36 being mounted in a bearing of a supporting yoke 38 but any other suitable supporting means may of course be employed. The guiding plane 34 is provided intermediate of its ends with a depending arm 39 which is suitably connected with an upper horizontally swinging arm 40 of a vertical rock shaft 41 which is journaled in suitable bearings of the frame of the machine. The shaft is provided at its lower end with an arm 42 which is connected by a rod 43 with an arm 44 of a steering shaft 45 mounted in an upright position in advance of the pilot's seat and equipped at its upper end with a steering wheel 46. The arm 40 may be connected with the depending arm 39 by a link 47 extending transversely of the machine to the side portion of the frame at which the vertical rock shaft 41 is located.

The aeroplane is equipped at the front with a propeller 48 which is driven by a suitable engine 49 and a searchlight 50 is preferably arranged centrally of the front end of the gas bag 4.

The aeroplane may be made of any desired size and it may be equipped with any suitable means for carrying passengers and the like and while one embodiment of the invention is illustrated in the accompanying drawings the claims define the actual scope of the same.

The frame of the machine is preferably 130

equipped with a central hanger 51 and any suitable retaining means may be employed for limiting the inflation of the gas bag.

What is claimed is:-

- 5 1. An aeroplane of the class described provided with a longitudinally disposed guiding plane pivotally mounted at its front and rear ends, and means for tilting the same in either direction laterally of the machine, said means including an arm depending from the guiding plane, an upright rock shaft having upper and lower arms, the upper arm being connected with the said depending arm and a steering wheel having a shaft connected with the lower arm of the rock shaft.
- 10 2. An aeroplane of the class described including a top plane mounted in a fixed position and provided with opposite gas pockets and a forwardly tapered longitudinally disposed guiding plane pivoted at its ends and extending rearwardly from the top plane, and operating mechanism connected with the guiding plane.
- 15 3. An aeroplane of the class described including a longitudinally disposed gas bag, a top plane located above the front end of

the gas bag and extending transversely of the aeroplane, side planes of substantially rectangular form extending from the machine at a point below the gas bag, rear planes located at opposite sides of the gas bag, a tilttable tail plane located in rear of the gas bag, a propeller, and guiding means.

4. An aeroplane of the class described including a longitudinally disposed gas bag, a top plane located above the front end of the gas bag and extending transversely of the aeroplane, side planes of substantially rectangular form extending from the machine at a point below the gas bag, rear planes located at opposite sides of the gas bag, a tilttable tail plane located in rear of the gas bag, a propeller located at the front of the machine and mounted below the gas bag and a guiding plane located above the gas bag and in rear of the top plane.

In testimony whereof I affix my signature in presence of two witnesses.

JOEL W. MILLICAN.
